GARAGE DOOR LATCH

Charles H. Ashton, Boulder Junction, Wis.

Application August 24, 1938, Serial No. 226,423

4 Claims. (Cl. 292—40)

My invention relates to garage door latches or latches for kindred purposes. Some aspects of my invention are not concerned with whether the latch be of the type which automatically engages upon closing the door, or of the type which requires manual movement when closed; other aspects of my invention are peculiar to these types. Also some aspects of my invention are concerned with a latch which is adapted to be locked while others are not concerned with whether the latch be locked or unlocked.

The objects of my invention include the provision of some or all of the following features in a door latch for garages and the like: one of a pair of doors may be bolted and the other locked to it; optionally, one of the doors may be bolted and locked by the use of the same hasp leaving the other door openable; the latch may be more or less permanently held in inoperative position so that either door may be closed without latching; the hardware constituting the latch may be packaged in a package whose over-all dimension is but a small fraction of the height of the door; an inexpensive provision is made for adjusting the latch to fit doors of varying height without the necessity of cutting or drilling any parts; a minimum of latch parts are exposed when the doors are shut and locked; the hasp of the latch is arranged to cover and protect the other working parts against tampering; in the event of working parts of the latch sticking due to rust, misalignment or bending, the leverage for manual operation can readily be increased over that normally used; the latch is readily installed; the latch is inexpensive yet rugged; and the door bearing the latch will automatically be latched upon closing the door.

Further objects, features and advantages of my invention are set forth in the following description of a specific embodiment thereof and illustrated in the accompanying drawings wherein:

Fig. 1 is an outside front elevation of a pair of garage doors embodying the latch of my invention;

Fig. 2 is a transverse vertical section taken on the line 2—2 of Fig. 1;

Fig. 3 is a vertical cross section similar to Fig. 2, but on an enlarged scale;

Fig. 4 is a front elevation of the hasp portion of the latch, being a fragment of Fig. 1 on an enlarged scale with portions of the hasp broken away to reveal the construction therewithin;

Fig. 5 is a plan section through the hasp and shaft of the latch taken on the line 5—5 of Fig. 4;

Fig. 6 is a rear elevation of the central portion

of the latch mechanism corresponding to Fig. 4, but looking from the rear side;

Fig. 7 is a fragmentary vertical section taken on the line 7—7 of Fig. 1 showing in transverse elevation the auxiliary staple for the hasp;

Fig. 8 is a rear elevation of the overlapping ends of the two rods which form in effect the lower bolt of the latch showing the adjustable connection therebetween, and may be considered as taken on the line 8—8 of Fig. 2; and

Fig. 9 is a plan section taken on the line 9—9 of Fig. 8.

In the drawings I have shown my latch as applied to a pair of garage doors 15 and 16 hinged to the door frame at their outer vertical edges. 15 My latch is carried by the left door 15. In general, upper and lower latch bolts 17 and 18 are reciprocally mounted at the inside of the left door 15 and adapted to be withdrawn by swinging the hasp 19, which is exposed at the front 20 of the door 15 and cooperates with a staple 20 carried on the outside of the right door 16.

As best shown in Figs. 4 and 5, the hasp 19 is hinged at its left end, by means of a pintle 21, to the left end of an inner leaf 22, preferably 25 of similar stock. The leaf 22 is fixed to the end of a stub shaft 23 by means of a bar-like diametrical projection 24 formed at the outer end of the shaft 23 which projects through a complementary slot in the leaf 22 and is peened thereover. For the purpose of manufacture and assembly, the shaft 23, leaf 22 and hasp 19 constitute a prefabricated unit.

A hole 25 for the shaft 23 is formed through the stile of the left door 15. Inner and outer annular escutcheon plates 26 and 27 border the hole 25 and are mounted by machine screws 28 countersunk in the plate 26, passing through the stile and threaded into tapped holes in the outer plate 27. The central openings in the escutcheon plates 26 and 27 form bearings for the shaft 23 which is passed therethrough. The inwardly protruding end of the shaft 23 carries one or more flats 29. A hub 30 is slipped over the inner end of the shaft and its bore is contoured to complement the flat or flats 29 as shown in Fig. 6. 45 The hub 30 is locked to the shaft 23 by a set screw 31. This in turn holds the shaft 23 against withdrawal, once it is assembled, by tampering from the outside of the door.

The hub 30 carries diametrically opposed ears 32 for operatively engaging the upper and lower bolts 17 and 18, which will now be described.

The lower end of the latch bolt 18 passes through a guide 33 in which it is reciprocably

mounted, and at its lower end extends into a hole 34 in a floor plate 35. The upper end of the lower latch bolt 18, as shown in Fig. 6, is offset and journaled by the aid of a cotter pin in one 5 of the ears 32. The upper latch bolt 17 is similarly pivoted at its lower end in the other ear 32, and its upper end engages in a hole 34' in the top plate 35'. The upper end of the latch bolt 17 is guided by passing through holes in the 10 inwardly directed ends 36 of a guide strap 37 carried on the inside of the door. A coil spring 38 interposed between lower end 36 of the guide strap 37 and a washer 39 fixed on the bolt tends to urge the bolt 17 upwardly and, by rotating 15 the hub 30 counterclockwise (Fig. 6) urge the lower bolt downwardly. The latch bolts 17 and 18 may be formed from single lengths of rod. But for two reasons I prefer to make each of 20 them of two rods arranged with adjustable overlapping ends; one is to cut down the overlength of the bolts in packaging for shipment; the other is to provide a convenient adjustment for effective length of the bolts, so that the rods do not have to be cut on the job, and so further operating 25 adjustments may be made from time to time in case the door sags.

In Figs. 8 and 9 I have illustrated the lower latch bolt 18 as formed from an upper rod 18a and a lower rod 18b with an adjustable interconnection therebetween. It will be understood 30 that substantially the same arrangement is here illustrated as applied to the upper latch bolt 17.

The overlapped ends of the rods 18a and 18b are locked together by means of a clamp 40. 35 This may be formed from a pair of identical plates 41 each having two semi-cylindrical grooves, so that when the two plates are put together with their grooves facing and are secured together by spot welding or riveting they form, 40 in effect, a twin tube for the reception of the respective overlapped ends of the rods 18a and 18b. A set of holes *a* to *k*, inclusive, are stamped in the plates 41 so that when the two plates are fixed together, the holes are diametrically opposite. Similar holes *A* to *G* are drilled through 45 the rods near their overlapped ends. By means of cotter pins 42 and 43 which pass through pairs of holes in the clamp 40 and through the holes in the rods, the rods 18a and 18b are fixed together to serve in lieu of a single rod to constitute the latch bolt 18.

Attention is invited to the arrangement and spacing of the holes in the clamp 40 and in the rods. Only a few widely spaced holes need be 50 drilled in the rods, and yet an adjustment for the effective length of the latch bolt to within an eighth of an inch may be had through a variation of two feet or so. Assuming the holes *a* and *f* are an inch and a half apart, they and the other 55 holes *b*, *c*, *d* and *e* are spaced a quarter of an inch apart (except that a hole between the holes *c* and *d* may be omitted). The holes *g*, *h*, *i*, *j* and *k* on the right hand side (Fig. 8) are spaced three-eighths of an inch apart with their terminal holes horizontally aligned with the holes *a* and *f*. The terminal hole *A* and the other hole *B* on one of the rods may be ten inches apart, while the holes *C*, *D*, *E*, *F* and *G* on the other rod may be spaced two and a half inches apart. 60 Some position can then be found for the clamp and the cotter pins 42 and 43 for every multiple of an eighth of an inch of overlap of the rods 18a and 18b throughout a range of about twenty inches. And if that range should not be enough, 65 the range can be increased ten inches by the sim-

ple expedient of providing a third hole in the rod 18b ten inches down from the hole *B*.

This arrangement gives a more positive coupling of the overlapped ends of the rods 18a and 18b than would a friction clamp or set screws, 5 and yet it avoids the expense of drilling a large number of holes in the rods or threading long reaches of the rods.

It will be understood that the upper latch bolt 17 may similarly be formed by two adjustable 10 overlapped rods. The forward portion of the floor plate 35 is preferably formed as an oblique apron 50. And somewhat similarly the top plate 35' has an inclined forward portion 50'. When the door is closed and the hasp 19 is not held 15 against rotation, the ends of the latch bolts will ride up the surfaces 50 and 50' axially shifting the latch bolts against the spring 38 and rotating the shaft 23 until the ends of the latch bolts reach the holes 34 in the plates, when the rods 20 will snap into the holes under the pressure of the spring 38, rocking the shaft 23 back to its normal position. The floor plate 35 may conveniently carry vertical flanges 51 serving as stops for the bottom corners of the two doors. 25 The top plates 35' may carry similar flanges, or wooden stop strips 52 may be employed.

The hasp 19 may be secured upon its staple 20 by a keeper 53, or it may be locked by a padlock upon the staple 20. Sometimes it is desirable to keep one of the doors locked to prevent removal of an automobile, but still permit free use of the other door for access to the garage. This may be effected by swinging the hasp 19 about its pintle 21 through 180° to cooperate with 30 an auxiliary staple 54 mounted by a plate 55 on the left door (Fig. 1). A padlock may then be slipped on the staple 54 to prevent rocking of the shaft 23 and thereby lock the left door.

The lower half of the auxiliary staple plate 40 55 may be extended into a forwardly offset flange 56 disposed at a radius to the shaft 23. When the hasp 19 is swung back to its left position, it may optionally be rotated to catch beneath the flange 56. When that is done the shaft 23 is 45 held in a sufficiently rocked position to withdraw the latch bolts and permit either door to be opened or closed at will, without the left door latching itself when closed.

When the hasp 19 is in the position of Fig. 1 50 and padlocked to the staple 20, it precludes opening of the left door because the shaft 23 cannot be turned to withdraw the latch bolts. It prevents opening the right door because the hasp 55 overlies the free margin of the right door. The hasp 19 overlies the peened-over end of the shaft projection 24 to protect it against attempts to remove the leaf 22 from the shaft. Both the hasp 19 and the hasp leaf 22 overlie the ends of the screws 28 and prevent their removal from 60 without. The shaft 23 together with the hasp and its leaf 22 cannot be pulled forwardly from the door because the shaft is locked to the hub 30 by the set screw 31, which may enter a counterbore in the flat 29.

Should the turning of the shaft 23 to withdraw the latch bolt become difficult because of rusting, jamming, misalignment or jamming of the parts, additional leverage may readily be applied to the 70 rocking of the shaft by the simple expedient of swinging the hasp 19 back about its pintle toward its leftmost position to give additional leverage. For ordinary use, however, I contemplate that the shaft may be rocked to withdraw the latch 75

bolts by merely swinging the hasp 19 out far enough to clear the staple 20.

When the hasp 19 is swung out, either door may be opened independently of the other unless an astragal 57 be used. An astragal is not necessary to lock the right door shut when the left door is locked, because the hasp 19 and the keeper 53 or padlock will do that; the astragal may be desirable for its weatherstripping effect.

10 It will thus be seen that by my invention I have provided a garage door latch which is fairly tamperproof when locked; which provides for various permutations of latching, locking and freedom for the two doors; which is easy of application without the necessity of performing many structural operations upon the latch hardware to fit it to various doors; which is easily adjustable to different heights of doors or to compensate for siding; which is simple and economical to manufacture; and which may be merchandised in packages of relatively small over-all dimensions.

I claim:

1. A door latch for a pair of doors hinged at their opposite lateral edges, comprising upper and lower latch bolts mounted for vertical movement on one door near its free edge, the upper end of the lower bolt and the lower end of the upper bolt being pivotally connected, the upper and lower latch bolts each consisting of a pair of rods having a combined length greater than the distance from the pivotal connection to the upper and lower edges of the door respectively, sleeves to secure each pair of rods together, said sleeves having a plurality of apertures relatively close together, and said rods having a plurality of apertures spaced relatively far apart.

2. Door latch mechanism comprising latch bolts to be mounted on the back side of a door and extending in opposite directions from a common reciprocating member connected to their respective near ends, each latch bolt being formed from two overlapping rod-like sections, and means for adjustably interconnecting the overlapped ends

of the two sections to provide various effective lengths for the bolt, said connecting means comprising a unitary pair of sleeves for receiving the respective sections, one of the sleeves having several longitudinally spaced apart holes whereby 5 a pin may pass through any one of the holes and a hole in the received rod section to anchor the section to the sleeve, and the other sleeve has several longitudinally spaced holes spaced at intervals different from the spacing of the holes 10 in the one sleeve and a pin extending through any of the holes in the other sleeve and through a hole in the received rod section.

3. Door latch mechanism according to claim 2 wherein one of the rod sections has a plurality 15 of pin receiving holes longitudinally spaced therealong at intervals, which intervals are between one and a half and two times the distance between the first and last holes in the set of holes in the sleeve which receives the section. 20

4. A door latch for a pair of doors hinged at their opposite lateral edges, comprising oppositely extending bolts mounted on the back side of one door near its free edge for opposite movement into and out of latching engagement with keepers, 25 each of said bolts being formed of adjustably secured-together overlapping rods, a shaft passing through the one door, crank arms on the inner end of the shaft connected to the near ends of the bolts whereby the bolts are withdrawn by rotation of the shaft, a two-leaf hasp, the under leaf of which is fixed to the outer end of the shaft and the outer leaf of which is hinged about a vertical axis to the end of the under leaf on the side of the shaft laterally remote from the free edge of 35 the one door and normally overlies the under leaf and the end of the shaft and protrudes beyond the free edge of the door to overlie the free lateral margin of the other door, and means on the other door cooperating with the protruding end of the 40 outer leaf to lock the other door thereto and to lock the hasp, and thereby the shaft, against rotation.

CHARLES H. ASHTON.
